DESIGN FOR A STARTER

Vera C. Hodges, Los Angeles, Calif.

Application February 6, 1945, Serial No. 117,783

Term of patent 14 years

(Cl. D26—5)

To all whom it may concern:

Be it known that I, Vera C. Hodges, a citizen of the United States, residing in the city of Los Angeles, county of Los Angeles, and State of California, have invented a new, original, and ornamental Design for Starter, of which the following is a specification, reference being had to the accompanying drawing, forming part thereof.

Fig. 1 is a perspective view of a starter, showing my new design.

Fig. 2 is a side elevational view.

Fig. 3 is an end elevational view, looking from the left end in Fig. 2.

Fig. 4 is an end elevational view, looking from the right end in Fig. 2.

I claim:

The ornamental design for a starter, substantially as shown.

VERA C. HODGES.
